UNITED STATES PATENT OFFICE.

JOSEPH H. BOLF, OF MUNCIE, INDIANA, ASSIGNOR TO GLEASON WORKS, OF ROCHESTER, NEW YORK, A CORPORATION OF NEW YORK.

APPARATUS FOR FEEDING THE LAPPING COMPOUND TO GEARS.

Application filed February 15, 1928. Serial No. 88,380.

The present invention relates to lapping machines and processes and particularly to methods and machines for lapping gears.

The primary object of this invention is the provision of an improved method and apparatus for feeding the lapping compound to the gears to be lapped.

One way of securing the desired smooth tooth surface finish on cut gears is by lapping. This process consists in running the two gears of a pair together, after they have been hardened, in the presence of a suitable lapping compound, usually a mixture of an oil and an abrasive. The lapping action produces tooth surfaces which are smooth and highly polished and lapped gears will run together in use very quietly.

Heretofore two methods have been most generally employed for applying the lapping compound to the gears. In one method the lapping compound is put on with a brush by hand. In the other and more usually employed method, the lapping compound is fed to the gears by a chain which runs over a grooved nut which is secured to one of the gear spindles. The chain dips into a reservoir or basin containing the lapping compound. As the gear spindle rotates the chain moves and thus carries the compound to the gears. Putting the lapping compound on by hand with a brush is a tedious and expensive operation and it has been more generally discarded in favor of the chain. One serious drawback to the method of feeding by a chain, however, is the tendency of the chain to become tangled at times in the gears, which may result in breakage of the teeth or even more serious damage.

The present invention aims to provide means, which may be readily controlled and which will operate automatically and with complete safety, for feeding the lapping compound to gears. The present invention resides in projecting the lapping compound into a stream by means of compressed air and directing said stream upon the gears to be lapped. The air atomizes the compound to a certain extent so that the amount used may be readily controlled. It is safe and inexpensive.

In the accompanying drawings, I have illustrated a preferred embodiment of my invention. It will be understood, however,

that the invention is capable of further modification within its scope and within the 55 limits of the appended claims.

In the drawings:

Fig. 1 is a front elevation, partly in section, showing a pair of gears in lapping position and one embodiment of apparatus constructed according to this invention for feeding the lapping compound to the gears; and

Fig. 2 is a sectional view taken at right angles to Fig. 1.

In the drawings, 10 and 11 indicate respectively the gear and pinion spindles of a bevel gear lapping machine of any usual suitable structure. Upon these spindles are mounted the gear 12 and pinion 13 respectively. In lapping the gears, they are run together with 70 a lapping compound on their contacting surfaces. 14 indicates a reservoir or basin, of any suitable structure, such as usually provided on lapping machines of the character described. This reservoir is adapted to contain the lapping compound, indicated at 15, which may be of any suitable character, usually a mixture of an abrasive, as oilstone powder, carborundum, alundum, etc., and oil. For spreading this compound on the gears, 75 I employ compressed air. 16 designates a conduit which passes through the basin or reservoir 14 and extends to the vicinity of the gears to be lapped. This conduit is apertured as at 17, below the level of the 80 compound in the reservoir, to form a passage through which the compound may flow into or be admitted to the conduit. The compressed air is directed into the conduit through the pipe 18 and nozzle 19. The 85 compressed air blast acts to force the compound into the conduit and through the same onto the gears. The air blasts atomizes the compound to a certain extent so that by 90 controlling the area of the feed passage 17 or by varying the air pressure, the amount of compound spread on the teeth may be controlled. The nozzle 19 is screw-threaded into the cap 20, which threads into an opening 95 in the basin or reservoir 14, and may be adjusted up and down to vary the area of the feed passage. The upper section 21 of the conduit will, preferably be made semi-rigid 100 or flexible so that the spray may be directed readily to the desired portions of the gears, 105 in the drawings, to a point just ahead of

where the gears come into mesh. If desired, a nozzle may be attached to the upper section 21 to concentrate the compound, more readily, on the gears.

5 The compressed air may be obtained by means of a pump which may be mounted on a machine or from an air-line, with which most factories are ordinarily equipped. To protect the operator from the spray, a guard 10 22 may be provided, which is hingedly connected to the reservoir or basin 14.

To prevent the lapping compound from flowing back into the line 18, when the air is shut off, a check valve, indicated at 15 23 may be provided. This valve may be of any suitable structure.

The use of compressed air is not only efficient and economical, but it safeguards 20 gears and machinery. The embodiment of the invention illustrated has a further advantage, namely, that by directing the air-blast through the reservoir, the compound is kept constantly stirred up, so that the abrasive 25 particles will not settle to the bottom and so that a lapping compound of uniform consistency may be insured.

While I have illustrated my invention in connection with a particular embodiment, it will be understood that this invention is 30 capable of further modification within its scope and the limit of the appended claims, and that this application is intended to cover any variations, or adaptations of the invention following, in general, the principles of 35 the invention and including such departures from the present disclosure as come within known or customary machine shop practise and as may be applied to the essential features hereinbefore set forth and as fall within 40 in the limits of the appended claims.

Having thus described my invention, what I claim is:

1. In a machine for lapping gears, a pair of spindles upon which the gears to be lapped are mounted, a reservoir located directly beneath said gears containing a lapping compound comprising a mixture of an abrasive and a liquid medium in predetermined proportions, a conduit extending to the vicinity of said gears, said conduit being provided with an aperture below the level of the lapping compound in the reservoir and an air discharging nozzle extending into the conduit adjacent said aperture, whereby said lapping compound is agitated and thereby mixed and conveyed from the reservoir to the gears purely by air pressure returning substantially unaltered to the reservoir.

2. In a gear lapping machine, a pair of spindles upon which the gears to be lapped are mounted, a reservoir located directly beneath said gears containing a lapping compound comprising a mixture of an abrasive and a liquid medium in predetermined proportions, said reservoir being provided with an opening in its bottom, a conduit threaded into said opening, said conduit extending to the vicinity of the gears to be lapped and being provided with apertures below the level of the lapping compound in the reservoir, an air discharging nozzle threaded into said opening and extending into said conduit with its discharge end adjacent the apertures in said conduit, and means for adjusting said nozzle in said conduit, the lapping compound being agitated and thereby mixed and conveyed from the reservoir to the gears purely by air pressure and returning substantially unaltered to the reservoir.

JOSEPH H. ROLF.
